UNITED STATES PATENT OFFICE.

WILLIAM H. LONSDALE, OF BROWNSBURG, QUEBEC, CANADA.

DRIVING ATTACHMENT FOR AUTOMOBILES.

Application filed May 3, 1924. Serial No. 710,945.

To all whom it may concern:

Be it known that I, WILLIAM H. LONSDALE, a citizen of the United States of America, residing at Brownsburg, Province of Quebec, Canada, have invented certain new and useful Improvements in Driving Attachments for Automobiles; and I do hereby declare that the following is a full, clear, and exact description of the invention, such as 10 will enable others skilled in the art to which it appertains to make and use the same.

The present invention pertains to an attachment for automobiles, the movement of which is controlled by a clutch pedal and 15 reverse pedal. The attachment is particularly adapted to Ford cars.

The object of the invention is the provision of means which may be applied to the control apparatus of a car of this character 20 in order to make the control movements thereof similar to the movements pertaining to automobiles of the more general type, wherein the high, low and reverse speeds are attained by an operating lever and the 25 clutch is actuated from a pedal.

It is well known that a person who has driven the more common type of car for a length of time becomes so accustomed to the movements thereof that he has great difficulty in driving a car of the Ford type. 30 The habit is most dangerous and asserts itself more readily when the driver in the Ford car finds himself in a tight position and must act quickly. Instead of executing 35 the movements necessary for the control of a Ford car, he is inclined to operate as if driving a car of the other type, and thus exposes himself to the possibility of accident. This difficulty is overcome by means 40 of the present invention, since a device constructed in accordance therewith and applied to a car of the Ford type renders the control movements of the car similar to those of a car of the more prominent type.

45 The invention is fully disclosed in the following description and in the accompanying drawings in which:

Figure 1 is a side elevation of the device applied to the transmission casing of a Ford 50 automobile, the device being in neutral position;

Figure 2 is a plan view corresponding to Figure 1;

Figure 3 is an elevation corresponding 55 to Figure 1, showing the position of parts when in reverse position;

Figure 4 is a similar elevation, in low speed position;

Figure 5 is a section on the line 5—5 of 60 Figure 1;

Figure 6 is a similar section showing the latch released from the sliding bars;

Figure 7 is a section on the line 7—7 of 65 Figure 2;

Figure 8 is a similar section showing the position of parts in high speed position;

Figure 9 is a section on the line 9—9 of 70 Figure 1;

Figure 10 is a side elevation showing the parts in high speed position;

Figure 11 is a fragmentary plan view 75 corresponding to Figure 10; and,

Figure 12 is a fragmentary elevation of the slow speed shaft and parts carried thereby.

Reference will now be had to these views by means of like characters which are employed to designate corresponding parts throughout.

The numeral 1 indicates the usual transmission casing of a Ford automobile, equipped with a cover 2 which has a substantially vertical extension 3 projecting rearwardly of the casing. The cover is formed with a large opening (not shown) 80 the latter being closed by means of a supplementary cover 4.

On the extension or platform 3 is mounted a box 5, the top of which is covered by a plate 6 having an H-slot 7. In the walls of the box is supported a sliding bar 8, to which is secured a substantially upright lever 9 projecting through the slot 7. One end of the sliding bar 8 carries a rod 10, from the lower end of which projects a finger 11, the purpose of which is pointed out below. A swinging plate 12 is pivoted as at 13 to the platform 3 and is formed with a slot 14 through which the rod 10 passes.

A substantially vertical bracket 15 is fixed to the forward edge of the platform 3 by means of bolts 16 which pass through the platform and through a perpendicular web 17 extending from the plate. To the rear edge of the platform is secured an angle bar 18. A pair of yokes 19 and 20 are supported for sliding movement by the members 15 and 18 and have their ends received in appropriate slots 21 and 21' cut through these members respectively. The forward end of the yoke 19 has a notch 19', while the 105 110

forward end of the yoke 20 has a similar notch 20', each of which is adapted for engagement in the slot 21.

The reverse pedal which forms part of the 5 Ford driving apparatus is removed, as may be seen from Figure 9. The slow speed shaft 22 is somewhat longer than usual in order to accommodate the block 23 keyed thereto and lying adjacent the hub 24' of the clutch 10 pedal 24. The hub 24' is loose on the shaft 22. From the block 23 extends an arm 25 having one end of a link 26 pivoted thereto, the remaining end of the link being pivoted to the forward end of the yoke 19 as may be 15 seen from Figure 4.

A fork 27 is supported by the upper part 20 of the bracket plate 15 and serves to support a rocker arm 28 pivoted therein. The lower end of this arm is pivoted to the forward end of the yoke 20, as shown in Figure 3. An arm 29 is secured to the reverse pedal shaft 30 and has pivoted thereto one end of a link 31, the remaining end of this link being pivoted to the upper end of the rocker 25 arm 28.

The clutch pedal 24 is free on the shaft 22 and is extended downwardly beyond this shaft, as indicated by the numeral 32. A 30 rocker arm 33 fixed to the usual clutch lever shaft 34 has one end thereof joined to the extension 32 by means of an adjustable link 35. The remaining end of the rocker arm carries a finger 36 from which extends a slotted plate 37. At the rear end of the 35 finger 36 is provided a stop member 38 adapted to engage the plate 12, as shown in Figures 2 and 6. A U-shaped lifter 39 pivoted to the lower part of the plate 15 is adapted for raising each sliding bar for releasing the notches 19' and 20' from engagement in the slots 21. The free end of the 40 latch has an extension 40 which is received in the slotted plate 37.

Assuming that the lever 9 is in neutral 45 position, that is between the legs of the H-slot, as shown in Figure 2, the clutch pedal 24 is pressed downwardly prior to any adjustment of the lever. In this connection it is to be noted that the clutch pedal must be 50 pressed before making any change in the transmission gearing. In order to throw the gearing into high speed, the lever is pulled to the right and into the shorter leg of the slot. As the rod 8 shifts, it swings the plate 55 12 out of the path of the stop 38. Since the clutch lever shaft 34 is under torsion, as usual, it is now free to turn its full extent whereupon the clutch is engaged for direct drive. The rocker arm 33 is brought to the 60 position shown in Figure 10 and raises the clutch pedal 24, so that the direct drive may be broken by pressing downwardly on this pedal.

To bring the machine into low speed, the 65 clutch pedal is pressed whereupon the rocker

arm 33 and parts carried thereby are returned to the position shown in Figure 1. The lever 9 is brought into the longer leg of the H-slot, whereupon the rod 10 engages the plate 12 and swings it outwardly into the path of the raised stop 38. A slight downward pressure is applied to the clutch pedal 24 and this raises the stop 38 from the swinging plate 12, as shown in Figure 6. The upward movement of the slotted plate 37 raises the pivoted lifter 39 to the position shown in Figure 6 in order to permit sliding of the yokes 19 and 20. The lever 9 is now turned into the lower end of the longer leg of the slot whereupon the finger 11 carried by the rod 10 slides the yoke 19 forwardly, as shown in Figure 4. During this movement, the yoke 20 is not displaced since it is disposed forwardly of the yoke 19, as shown in Figure 1. At the end of its stroke, the finger 11 rides on the curve 41 formed at the forward end of the body of the yoke 20. Through the medium of the link 26 and arm 25, the slow speed shaft 22 is turned in the same manner as by the usual clutch pedal 90 on the Ford car. Pressure on the clutch pedal is released, whereupon the parts actuated thereby are returned to the position shown in Figure 1. The lifter 39 is likewise 95 returned to the position shown in Figure 5 and allows the notch 19' of the yoke 19 to engage the slot 21 to lock the yoke 19 in place.

In order to reverse, the lifter 39 is operated by a slight downward pressure on the clutch pedal 24 as already described. The lever 9 is pushed into the forward end of the longer leg of the H-slot, whereupon the finger 11 carried by the rod 10 draws the yoke 20 rearwardly to the position shown in Figure 3. The finger travels in the open part of the yoke 19, and upon reaching the end of its stroke rides on the curve 42 formed at the rear end of this yoke. It will thus be seen that no movement is imparted to the yoke 19. At the end of the stroke the notch 20' of the yoke 20 is in alignment with the slot 21 of the plate 15. The pressure on the clutch pedal is now released whereupon the lifter 39 and yoke 20 are lowered, due to 110 the torsion on the clutch lever shaft 34, whereby the notch 21' is brought into engagement in the receptive slot 21 of the plate 15.

When shifting into high, the lifter 39 is 115 again raised and the lever 9 is carried to the position shown in Figure 11. The swinging plate 12 is engaged by the rod 10 and carried out of the path of the stop 38. The torsion on the shaft 34 now swings the rocker arm 33 to the limit shown in Figure 10, whereupon a direct drive is established as already pointed out.

While a specific embodiment of the invention has been illustrated and described, it is 130

to be understood that various alterations in the details of construction may be made without departing from the spirit of the invention as indicated by the appended claims.

5 Having thus fully described the invention, what I claim as new and desire to protect by Letters Patent is:—

1. A driving attachment for an automobile having a transmission casing containing variable gearing and a clutch pedal shaft adapted to set said gearing for low speed, comprising a yoke slidably supported by said casing, an operative connection between the yoke and the shaft, a slideable bar supported by the casing, an operating lever for shifting said bar, and a rod secured to the bar and adapted to engage said yoke.

2. A driving attachment for an automobile having a transmission casing containing variable gearing and a shaft journaled in said casing and adapted for the adjustment of the gearing, comprising a yoke slidably supported by said casing, an operative connection between the yoke and the shaft, a slideable bar supported by the casing, an operating lever for shifting said bar, a rod secured to the bar and adapted to engage said yoke, a pedal loosely mounted on said shaft, and a locking device for said yoke operatively connected to said pedal.

3. A driving attachment for an automobile having a transmission casing containing variable gearing and a clutch pedal shaft adapted to set said gearing for low speed, comprising a yoke slidably supported by said casing, an operative connection between the yoke and the shaft, a slideable bar supported by the casing, an operating lever for shifting said bar, a rod secured to the bar and adapted to engage said yoke, a clutch pedal loosely mounted on said shaft, and a locking device for said yoke operatively connected to said pedal.

4. A driving attachment for an automobile having a transmission casing containing variable gearing, a clutch pedal shaft adapted to set said gearing for low speed, and a reverse pedal shaft adapted to set said gearing for reverse movement, said attachment comprising a pair of yokes slidably supported by the casing and operatively connected to said shafts, a slideable bar supported by the casing, an operating lever for shifting said bar, and a rod secured to said bar and adapted for selective engagement with said yokes.

5. A driving attachment for an automobile having a transmission casing containing variable gearing, a clutch pedal shaft adapted to set said gearing for low speed, and a reverse pedal shaft adapted to set said

gearing for reverse movement, said attachment comprising a pair of yokes slidably supported by the casing and operatively connected to said shafts, a slideable bar supported by the casing, an operating lever for shifting said bar, a rod secured to said bar and adapted for selective engagement with said yokes, a clutch pedal loosely mounted on the clutch pedal shaft, and a locking device for said yokes operatively connected to said pedal.

6. A driving attachment for an automobile having a transmission casing containing variable gearing, a clutch pedal shaft adapted to set said gearing for low speed, and a clutch lever shaft adapted to establish direct drive from said gearing, said attachment comprising a yoke slidably supported by said casing, an operative connection between the yoke and the clutch pedal shaft, a slideable bar supported by the casing, an operating lever for shifting said bar, a rod secured to the bar and adapted to engage the yoke, a clutch pedal loosely mounted on the clutch pedal shaft, a rocker arm fixed to the clutch lever shaft and connected to the clutch pedal, a latch for locking said yoke, a keeper for said latch carried by the rocker arm, a stop carried by the keeper, a plate pivoted to the casing, said plate being engageable by said rod for movement into and out of the path of the stop by actuation of the operating lever.

7. A driving attachment for an automobile having a transmission casing containing variable gearing, a clutch pedal shaft adapted to set said gearing for low speed, a reverse shaft for reversing the movement of said gearing, and a clutch lever shaft adapted to establish direct drive from said gearing, said attachment comprising a pair of yokes supported by the casing and operatively connected to the clutch pedal shaft and reverse shaft respectively, a slideable bar supported by the casing, an operating lever for shifting said bar, a rod secured to the bar and adapted for selective engagement with said yokes, a clutch pedal loosely mounted on the clutch pedal shaft, a rocker arm fixed to the clutch lever shaft and connected to the clutch pedal, a latch for locking said yokes in adjusted positions, a keeper for said latch carried by the rocker arm, a stop carried by the keeper, a plate pivoted to the casing, said plate being engageable by the rod for movement into and out of the path of the stop by actuation of the operating lever.

In witness whereof I have hereunto set my hand.

WILLIAM H. LONSDALE.
